UNITED STATES PATENT OFFICE.

WILBUR L. SHEPARD, OF ELMWOOD, CONNECTICUT, ASSIGNOR TO THE WORLD GAS ENGINE COMPANY, OF HARTFORD, CONNECTICUT, A CORPORATION OF MAINE.

ENGINE.

1,283,575.

Specification of Letters Patent.

Patented Nov. 5, 1918.

Application filed April 13, 1918. Serial No. 228,484.

To all whom it may concern:

Be it known that I, WILBUR L. SHEPARD, a citizen of the United States, residing at Elmwood, in the county of Hartford and 5 State of Connecticut, have invented certain new and useful Improvements in Engines, of which the following is a specification.

This invention relates to engines. An engine involving the invention can be employed with advantage in many different fields; as an illustration I might mention its use in conjunction with an automobile. It can be also utilized with any necessary modifications for the propulsion of an aero- 15 plane. In like manner the motive agent may be of any suitable character, although a hydrocarbon such for instance as gasolene answers the purpose in a satisfactory way.

I have several fundamental purposes in 20 view as I will more fully set forth in the following description, wherein I will outline in detail that form of embodiment of the invention which I have selected for illustration in the accompanying drawings forming part of the present specification. As 25 will be obvious I do not restrict myself to this particular disclosure; I may depart therefrom in several respects within the scope of the invention defined by the claims 30 following said description. To return again to the initial motive of the invention; it is the production of an engine by which the use of valves certainly those of the ordinary type are wholly eliminated, in view of 35 which circumstance certainty of action, simplicity of construction, ready assemblage of parts and like factors are possible.

Referring to said drawings:

Figure 1 is a sectional side elevation of 40 an engine involving the invention.

Fig. 2 is a transverse section on the line 2—3 of Fig. 1, looking toward the right.

Fig. 3 is a similar section on the same line but looking toward the left in said 45 Fig. 1.

Fig. 4 is an inside face view of a valve ring, and

Fig. 5 is a cross section of the same.

Like characters refer to like parts throughout the several views.

The engine comprises in its construction a main shaft such as that denoted in a general way by 2. This main shaft in the present case is fixed or stationary as is the corresponding part in my contemporaneously

pending application filed September 19, 1917, Serial No. 192,062. Associated with the main shaft 2 is what might be considered a cylinder-carrier such as that denoted in a general way by 3. As shown said cylinder-carrier is in the form of a spool and involves a hub or elongated sleeve 4 fitted around and supported by the main shaft 2, and two end flanges 5 and 6. There may be any desirable number of cylinders as 7, 60 five of them being shown. Each is supported by the rotary carrier 3 for revolution around the main shaft 2; the cylinders are spaced equal distances apart and the ends of them have external threads to fit corresponding threads in openings as 8 in the end flanges 5 and 6 respectively as shown for instance and probably best in Fig. 1.

Each cylinder contains a piston 9 to the inner or forward end of which is jointed a 75 pitman or rod 10, the forward ends of the several pitmen or rods being articulated in turn to cranks as 11. These cranks extend into the casing 12 of virtually cylindrical form and rigid with the inner flange or disk 80 6. The circumferential portion of the casing 12 pivotally receives gudgeons or studs as 13 extending outward from the respective cranks 11, the latter respectively having inwardly extending and coaxial gudgeons 14 85 which are rotatively fitted in radial hubs 15 of the sleeve 16 which is fitted to and surrounds that part of the shaft 2 inclosed in the casing 12. Fastened to the inner gudgeons 14 as by screw-threading, are suitable 90 gears as the bevel pinions 17, the teeth of which as shown are in mesh with those of a master bevel gear 18 made rigid for instance by screw-threading, with and surrounding the main shaft 2 forward of the 95 carrier 3.

Said carrier 3 has a seat or cavity 19 to receive the ball-bearing 20 fitted to and around the shaft 2. The inner member of the ball-bearing as will be clear is rigid with the shaft 2 while the outer member of it is rigid and turns with the carrier 3. Adjacent to said ball-bearing 20 is a second bearing 21, it and the adjacent face of the master bevel gear 18 having peripheral grooves or 100 channels to receive the balls of said bearing 21. The bearing 20 is to take care of radial thrusts, while the bearing 21 compensates for end thrusts.

The sleeve 16 has an annular flange 22 110

fastened as by the screws 23 to the outer or forward wall of the casing 12. This casing it might be noted contains the several gears and adjunctive devices which I have described, and it may be filled or partly filled by suitable oil to lubricate the parts mentioned. The flange 22 has a cavity 24 to receive a ball-bearing 25, the inner member of the ball-bearing being rigid with and surrounding the shaft 2 while the outer member thereof is tightly fitted in the cavity 24 so as to rotate with the carrier 3 and casing 12. The balls of this bearing 25 compensate for radial thrust. Surrounding the two just outside the casing 12 is the hub 26 provided with the flange or web 27 connected as by screws 28 with the casing 12. This hub 26 has extending from it the hollow shaft 29 which as will be understood rotates with the casing 12 and carrier 3. The shaft 29, therefore, presents a convenient means for applying the power of the engine. Around the shaft 2 is a ball-bearing 30 set in the concavity 31 of the left head or flange 5 of the spool-like carrier 3, this ball-bearing being adapted to compensate for radial thrusts, the adjacent ball-bearing 32 compensating for end thrusts.

In the ordinary acceptation of the term the engine is really valveless. That is to say there are no puppet, globe or like valves such as are customarily found in the usual gas engine. There is a valve mechanism, however, of quite novel character as will later herein appear. Surrounding what is shown as the left end of the shaft 2 is the annular member 40 (Fig. 3) which might be considered as a combined supply and exhaust controlling element, because as shown it functions both in the delivery of the necessary agent to and the exhaust of the exploded agent from the several revoluble cylinders. This annular member comprises a hub 41 which can be connected as by the key 42 to the shaft 2, the part 40 bearing against the outer member of the ball-bearing 32 and being abutted in turn by the sleeve 43 threaded to the shaft 2.

Each of the heads of the cylinders 7, the heads being located at the left in Fig. 1, has as shown an approximately central opening 44 in which are respectively fitted the nipples or sleeves 45, there being as will be understood five of such nipples or sleeves. As shown the latter extend inwardly from the annular member or ring 46 which it might be explained fits at all times flatwise against the circular or ring body 47 of the annular member 40. As a matter of fact the annular member 46 is constantly yieldingly pressed against the circular or ring body 47 and for accomplishing this particular result the springs 48 are shown, there being five of such springs. They respectively surround nipples 49 projecting rearwardly from the

ends of the cylinders 7 and their terminals fit channels 50 and 51 formed respectively in said cylinder ends and ring 46. Obviously the annulus or ring 46 rotates or revolves and by this the supply and exhaust of the necessary fluid is accomplished in proper order. The annular body 47 as shown has an opening 52 for instance for the supply of the necessary operating agent to one or more cylinders, and it has further a practically similar opening 53 by which the exhaust can be accomplished. Fitted in the openings 52 and 53 are ducts or pipes as 54 and 55 respectively, the pipe 54 in the present instance being connected to a suitable source of supply which is assumed to be gasoline vapor, while the pipe 55 opens to atmosphere. The ring or circular portion 47 has as shown the elongated slot 56 which is practically of arcuate formation, the curvature conforming practically to that of said part 47. This slot or arcuate opening 56 is intersected by or is in direct communication with the supply opening or inlet 52. The part 47 has a second segmental slot 57 virtually a duplicate of the slot 56. The ring 47 consequently presents a circular runway for the complementary ring 46. It will be understood, of course, that the length of the slots 56 and 57 is considerably less than the extent of the annular part 45. Two ends of the two slots are comparatively close together, although there is a considerable distance between the other two ends. As it might otherwise be explained, the head end of the slot 56 is adjacent the tail end of the slot 57, while there is a considerable distance between the tail end of said slot 57 and the tail end of the slot 56. As I have already stated the duct or pipe 54 is connected with a suitable source of supply, and it will be supposed that the supply is on and that the cylinders 7 are revolving with their carrier 3. The ring 46 obviously turns with the cylinders and carrier, and when a tube as 45 reaches the slot 52 a supply of gaseous fluid enters the cylinder associated with said sleeve 45, as said cylinder revolves, the supply being stopped when the sleeve comes to the uncut portion of the part 40. When the firing pin is reached, the gaseous charge at this time being compressed, the charge will be fired, and as the cylinder continues its rotation and at the proper point, the tube 45 under discussion will come opposite the slot 57, so that the spent charge will pass into the slot 57 and thus into the opening 53 and duct or pipe 55 to atmosphere.

Between the tail end of the slot 52 and the head end of the slot 57, there is means for firing each compressed charge, and the means shown for this purpose will now be set forth. Each cylinder is equipped with a plug 58 extending through its head at a proper point and adapted to travel on the insulating ring 130

59. The shaft 2 supports the carrier 60 equipped with the pin 61 adapted to be engaged by the outer spherical end of each plug 58 as the cylinders revolve so as to successfully explode the charges therein.

The shaft 2 as shown has at one end, for instance the left in Fig. 1, a cavity or chamber 65 in which is fitted the plug 66 which may be of screw form. From this cavity 10 leads the channel or passage 67 extending longitudinally of the shaft and for practically its entire length. The chamber or cavity 65 by removing the plug 66 may be supplied with lubricant which flows along 15 the channel or passage 67. The latter is provided with branches as 68 and 69 for instance for conducting the lubricant to the anti-friction bearings to which I have referred. It may have the further branches 20 68' for the supply of the lubricant to the gearing and associated parts and may have other branches as 70 and 71 leading therefrom to lubricate other parts.

The group of cylinders 7 is surrounded by 25 rings or bands 75 and 76 near the ends thereof, and to these rings are fitted as by screws 77, the arcuate scoops or blades 78. The rear ends of these blades or scoops 78 are flared outwardly as at 79, the forward ends of the 30 scoops or fan blades 78 having elongated slots 81. The blades as will be seen upon inspection for instance of Fig. 2, extend outwardly a short distance beyond the circumference of the spool or carrier 3, their rear 35 ends abutting against the rear cylinders. The blades, however, extend uninterruptedly between the ends 5 and 6. As the carrier rotates, the scoops or blades draw in air which is directed against the surfaces of the 40 respective cylinders, and escapes to atmosphere through the slots 81. This effectually and adequately cools the several cylinders.

What I claim is:

1. The combination of a carrier, a plurality of engine cylinders, supported in approximately annular order by the carrier, each of the cylinders having an opening, a member provided with tubes extending into said openings, a second member fitted flatwise against the first member and having an opening, means for yieldingly forcing the two members into contact with each other, and means for securing a relative movement of said two members, to place the 55 openings of the tubes successively into register with the opening of the second member.

2. The combination of a carrier, a plurality of engine cylinders, supported in ap-

proximately annular order by the carrier, each of the cylinders having an opening, a member provided with tubes extending into said openings, a second member fitted flatwise against the other member and having an opening, springs surrounding the tubes and acting against the first member and tending to force the same into contact with the second member, and means for securing a relative movement of the two members to place the openings of the tubes into register with the opening of the second member. 65

3. The combination of a carrier, a plurality of engine cylinders supported in approximately annular order by the carrier, each of the cylinders having an opening, an annular member provided with tubes extending into the said openings, a second annular member fitted flatwise against the other annular member and having an opening, and means for securing a relative rotation of the two annular members to bring the openings 70 of the tubes successively into register with the opening in said second annular member. 75

4. The combination of a carrier, a plurality of engine cylinders supported in approximately annular order by the carrier, each of the cylinders having an opening, an annular member provided with tubes extending into said openings, a second annular member fitted flatwise against the other annular member and having two distinct 85 openings, and means for securing a relative rotation of the two annular members to bring the openings of the tubes successively into register with the openings in said second annular member. 90

5. The combination of a carrier, a plurality of engine cylinders supported in approximately annular order by the carrier, each of the cylinders having an opening, an annular member provided with tubes extending into said openings, spring means acting against said annular member and tending constantly to force the same outwardly, a second annular member fitted flatwise against the other annular member and having an opening, and means for securing a relative rotation of the two annular members to bring the openings of the tubes successively into register with the opening in said second annular member. 105

In testimony whereof I affix my signature in the presence of two witnesses.

WILBUR L. SHEPARD.
